CLAIM

The ornamental design for ornamental design for a cam lever mount for attaching firearm accessories to picatinny rails on firearms, as shown and described.

DESCRIPTION

FIG. 1 is an upper front right perspective view of the cam lever mount for attaching firearm accessories to picatinny rails on firearms with cam lever in closed position.

FIG. 2 is a right side view of the cam lever mount on firearm accessory of FIG. 1.

FIG. 3 is a left side view of the cam lever mount on firearm accessory of FIG. 1.

FIG. 4 is a front side view of the cam lever mount on firearm accessory of FIG. 1.

FIG. 5 is a rear side view of the cam lever mount on firearm accessory of FIG. 1.

FIG. 6 is a top view of the cam lever mount on firearm accessory of FIG. 1.

FIG. 7 is a bottom view of the cam lever mount on firearm accessory of FIG. 1.

FIG. 8 is an upper front right perspective view of the cam lever mount for attaching firearm accessories to picatinny rails on firearms with cam lever in open position.

FIG. 9 is a right side view of the cam lever mount on firearm accessory of FIG. 8.

FIG. 10 is a left side view of the cam lever mount on firearm accessory of FIG. 8.

FIG. 11 is a front side view of the cam lever mount on firearm accessory of FIG. 8.

FIG. 12 is a rear side view of the cam lever mount on firearm accessory of FIG. 8.

FIG. 13 is a top view of the cam lever mount on firearm accessory of FIG. 8.

FIG. 14 is a bottom view of the cam lever mount on firearm accessory of FIG. 8.

FIG. 15 is an upper front right perspective view of the closed cam lever mount of FIG. 1.

FIG. 16 is an upper rear left perspective view of the closed cam lever mount of FIG. 15.

FIG. 17 is an upper front left perspective view of the closed cam lever mount of FIG. 15.

FIG. 18 is an upper rear right perspective view of the closed cam lever mount of FIG. 15.

FIG. 19 is a bottom view of the closed cam lever mount of FIG. 15.

FIG. 20 is a right side view of the closed cam lever mount of FIG. 15.

FIG. 21 is an upper front right perspective view of the open cam lever mount of FIG. 8.

FIG. 22 is an upper rear left perspective view of the open cam lever mount of FIG. 21.

FIG. 23 is an upper front left perspective view of the open cam lever mount of FIG. 21.

FIG. 24 is an upper rear right perspective view of the open cam lever mount of FIG. 21.

FIG. 25 is a bottom side view of the open cam lever mount of FIG. 21.

FIG. 26 is a right side view of the open cam lever mount of FIG. 21.

FIG. 27 is an exploded view of the cam lever mount of FIG. 1.

FIG. 28 is a lower left front perspective view of the cam lever of FIG. 1.

FIG. 29 is an upper right front perspective view of the cam lever of FIG. 28.

FIG. 30 is a top view of the cam lever of FIG. 28.

FIG. 31 is a front view of the cam lever of FIG. 28.

FIG. 32 is a bottom view of the cam lever of FIG. 28.

FIG. 33 is a left side view of the cam lever of FIG. 28; and,

FIG. 34 is a right side view of the cam lever of FIG. 28.

The broken lines in FIGS. 1-14 are for illustrative purposes

and form no part of the claimed design.
